UNITED STATES PATENT OFFICE.

FRIEDRICH BANGERTER, OF NEW YORK, N. Y.

CLOCK.

1,211,383.

Specification of Letters Patent.

Patented Jan. 9, 1917.

Application filed June 3, 1911. Serial No. 631,068.

To all whom it may concern:

Be it known that I, FRIEDRICH BANGERTER, a citizen of the Republic of Switzerland, and a resident of the city of New York, borough 5 of Richmond, county of Richmond, and State of New York, have invented certain new and useful Improvements in Clocks, of which the following is a specification, such as will enable others skilled in the art to 10 which it appertains to make and use the same.

This invention relates to clocks, and particularly that class wherein a pendulum escapement is employed and wherein the 15 clock-train is weight driven.

It is well known to those skilled in the art that the most accurate and reliable clocks are those which are driven by a weight. Most of such clocks are provided with a plurality of weights, one being used to supply 20 the energy necessary to strike the time, and the other the energy for operating the clock-train, and in clocks of such construction they have to be wound frequently, usually either 25 daily or weekly.

Many attempts have been made to produce clocks which will run for a relatively long time without requiring the attention of an attendant to wind the same. In such clocks, 30 (other than electrical clocks) powerful springs have been employed, one of such springs being used for time-striking and the other for actuating the clock-train. Clocks of this class designed to run for an extended 35 length of time, such, for example, as a period of say a year or more, have been indifferent time-keepers due to the fact that the power of the springs becomes materially lessened during the latter part of the cycle 40 of operations. Therefore, spring-operated clocks, calculated to be run for any great length of time, have been more or less unsatisfactory and have not gone into very extensive use.

The object of this invention is to provide 45 a clock which will require the attention of an attendant but once in a long period of time and which will also be an accurate time-keeper.

A further object is to provide a power- 50 device, transmission mechanism and automatic devices connected thereto, whereby the power of said power-storage mechanism is utilized to wind up the clock,—that is to say, 55 to lift the clock-train operating weight, at certain definitely recurring intervals of time.

A further object of my invention is to provide, in connection with such power mechanism, time-striking means operated by said power-device, which being independent of the clock-train operating means does not interfere therewith.

A further object of my invention is to provide a single power-device which will afford the power to strike the time and effect 60 the winding of the clock, doing away with two sets of mechanism (one for each purpose), as heretofore used.

A further object of my invention is to provide such a power-device that with one winding 65 of the same the clock may be kept running, and also striking the time, for a year or more in duration.

A further object of my invention is to provide means in connection with said 70 power-storage device whereby the winding of the clock-train does not interfere with continuous running and perfect time-keeping of the clock, and does not require any supplemental propelling mechanism for the 75 clock-train during the winding operation.

Other objects such as simplicity, durability and economy of manufacture will be readily apparent from the following description, in connection with the accompanying 80 drawings, in which,—

Figure 1 is a front elevation showing the power-transmission and weight-lifting mechanism; Fig. 2 is an end elevation showing the power-storage device for operating 85 the time-striking mechanism and the weight-lifting mechanism; Fig. 3 is a section on line 3—3 of Fig. 2, and showing the clock-train, and other operative mechanism; Fig. 4 is a rear elevation of the mechanism shown 90 in Figs. 2 and 3; Fig. 5 is a vertical section on line 5—5 of Fig. 6; and Fig. 6 is a horizontal section on line 6—6 of Fig. 5.

Referring to the construction illustrated, A represents a clock casing, which may be 95 of any appropriate form, within the upper portion of which is suitably mounted the clock dial B, and at the rear thereof the clock-train indicated in whole at C. Within the lower portion of said casing is housed 100 the power device indicated in whole at D, for actuating the time-striker, as well as for operating the weight-lifting mechanism.

The clock-train is of the usual construction, comprising the great wheel E, suitably mounted upon the clock train casing, indicated at E', which wheel is driven, 105

through the pinion E^2 , by means of the endless chain indicated at E^3 . The great wheel E , drives the center wheel E^4 through the lantern wheel E^5 , and the wheel E^4 , in turn, 5 drives the end wheel E^6 , through the lantern wheel E^7 , and the wheel E^6 drives the escapement wheel E^8 through the lantern wheel E^9 , the latter being controlled by the escapement E^{10} , (the pendulum for governing the same not being shown), all, as is 10 well known, in the art. Keyed to a shaft F which may be suitably mounted in bearings rigidly secured within the casing A , are a sprocket wheel F' , and a smaller sprocket 15 wheel F^2 , both rotating with said shaft. Engaging the teeth of the sprocket wheel F^2 is the endless chain E^3 hereinbefore referred to. Said endless chain carries within one bight thereof a roller or pulley G , 20 having an axle G' suspended from which, is a small weight G^2 , the purpose of which weight is to keep the said endless chain in position upon the teeth of the respective sprocket wheels F' , F^2 as well as to keep 25 the chain distended.

Mounted within another bight of the endless chain E^3 is a roller H similar in all respects to the roller G just described, from which is suspended the clock-train driving weight H' . It will be observed that said 30 weights remain suspended in perpendicular positions while the rollers G and H are free to turn and both the weights and rollers are capable of being moved in a perpendicular 35 plane.

The power or winder-device, indicated in whole at D comprises the shaft I , having its bearings in the side supports I' , I^2 , to 40 which shaft is secured one end of a powerful spiral spring I^3 , the other end of which spring is secured to the inner surface of the barrel I^4 , the outer surface of which is provided with a drive gear I^5 , said barrel and gear being free to turn upon the shaft I under propulsion of said spring. 45

Rigidly mounted upon the shaft I is a winder gear J , which is adapted to be driven by the pinion J' meshing therewith, the latter being mounted upon the shaft J^2 having 50 its bearings in the side supports I' , I^2 . Also rigidly mounted upon the shaft I is a ratchet wheel J^3 , engaging which is a pawl J^4 mounted upon the side support I^2 and kept in engagement with said ratchet wheel by the spring J^5 , also mounted upon 55 said side support, the function of said ratchet wheel and pawl being to prevent the unwinding of the spring I^3 after the same is wound. The winder pinion J' may be actuated by a key or crank (not shown), or in any other suitable manner. Also mounted upon the side supports I' , I^2 is a shaft K , 60 which at one end carries a pinion K' , meshing with the barrel drive gear I^5 and is

driven thereby. Upon the opposite end of the shaft K is a gear K^2 , which is adapted to drive the shaft K^3 , (also having its bearings in the side supports I' , I^2), through the pinion K^4 . The gear K^2 is also adapted 70 to drive the shaft K^5 through the pinion K^6 , said shaft having one of its bearings in the side support I^2 , and the opposite end bearing in a support K^7 secured to a bracket K^8 , mounted upon the side frame I' . 75

The shaft K^3 is provided with a gear wheel K^9 , keyed thereto, the outer surface of which gear wheel is provided with an annular groove or cam slot K^{10} and also a stop recess K^{11} for the reception of the cam pin 80 to be hereinafter referred to.

Mounted within bearings in the bracket K^8 are a plurality of escapement gears and pinions comprising the pinion K^{12} , driven by the gear K^9 . The pinion K^{12} is integral 85 with a gear K^{13} , meshing with a pinion K^{14} , carrying a worm wheel K^{15} , the teeth of which engage and are controlled by a worm K^{16} forming part of a governor shaft K^{17} rotatably mounted within the bracket K^8 , 90 and carrying the governor wings K^{18} , it being also provided with a stop arm K^{19} , adapted to contact with a stop K^{20} on one end of an escapement lever to be presently described, the function of which governor is 95 well known, it being adapted to regulate the speed at which the escapement pinions and gears may rotate.

Pivotedly mounted upon a screw bolt L' secured to the exterior side of the bracket K^8 is an escapement lever L , secured by the screw L' , and normally held in a horizontal position by means of a spring L^2 carried by the bracket K^8 . The forward end of said lever carries a cam pin L^3 , the head of which is located within the cam slot K^{10} and is normally held in the stop recess K^{11} under the action upon the lever L of the spring L^2 . The lever L also carries a connecting pin L^4 carrying one end of a connecting rod L^5 , 100 the function of which is to lift the lever L and release the cam pin L^3 from the stop recess K^{11} , the operation of which will be hereinafter referred to. 105

Loosely mounted upon a shaft M rigidly secured to the side support I' is a time-striker driving gear M' , which is adapted to be driven by a pinion M^2 secured to the outer end of the shaft K^3 . Also mounted 110 upon the shaft M and secured to the gear M' so as to rotate therewith is a time-striker ratchet-wheel N , whose periphery is formed with a series of ratchet teeth corresponding in number to the hours of the day, said teeth 115 being more clearly shown at N' in Figs. 4 and 6. Also mounted upon the side support I' by a bracket O is a bell gong O' , juxtaposed to which is a bell hammer O^2 mounted upon one end of a hammer arm O^3 , the 120 125 130

- lower end of said arm being rigidly mounted upon a short shaft O^4 , pivotally secured to a bracket O^5 and the side support I' . The lower end of the hammer arm O^3 is so formed as to constitute a pawl O^6 , which is adapted to engage the ratchet teeth N' of the time-striker ratchet wheel N . The bracket O^5 is provided with a hammer-actuating spring O^7 , the upper end of which is bent to engage the hammer arm O^3 . It will be observed that in the rotation of the time-striker wheel N in the direction of the arrow, the ratchet teeth N' reciprocate the pawl O^6 , and when the latter engages the depressions between the ratchet teeth, the hammer O^2 will be propelled forwardly under the action of the spring O^7 , to strike the bell or gong O' , the action of the ratchet teeth being to alternately move the pawl O^6 outwardly against the action of the spring O^7 and release the same in the act of engaging the next succeeding tooth when it is free to be moved in the opposite direction under the action of said spring.
- 25 Mounted upon a post on the inner side of the clock casing A is a lever P , pivoted at P' , one end of which lever is provided with a pin P^2 , adapted to hold the upper end of the connecting rod L^5 . The opposite end of the lever P is slightly weighted, and provided with a regulating screw P^3 , and this arm of the lever, by means of the upper end of said regulating screw is adapted to be engaged by the weight H' so as to raise the opposite end of said lever and thereby, through the rod L^5 and the lever L release the cam pin L^3 from the cam recess K^{11} and permit the rotation of the escapement gears and pinions mounted within the bracket K^8 , it being seen that when so released a full revolution of the wheel K^9 is permitted.
- 30 Mounted upon the shaft K^5 is a sprocket wheel Q , driven by said shaft, the teeth of which engage an endless sprocket chain Q' , whereby said wheel drives the sprocket wheel F' hereinbefore referred to, and, through the shaft F the smaller sprocket wheel F^2 carrying the endless sprocket chain E^3 before described, for driving the clock-train.
- 35 The operation of the apparatus will be quite clear from the foregoing description and the drawings illustrating the same.
- 40 It will be observed that the weight H' which drives the clock-train is supported in part by the sprocket wheels F^2 and E^2 , and the gradual lowering of the weight H' driving the pinion E^2 and associated wheel-train under control of the escapement E^{10} .
- 45 In this operation those sections of the endless chain E^3 lying between the roller H and the sprocket wheels E^2 , F^2 , which sections are designated respectively as 1 and 2, are gradually lengthened through the rotation of the sprocket wheel E^2 , while, how- ever, the sprocket wheel F^2 does not rotate and, as the weight H' is lowered by the lengthening of the sections 1 and 2, the roller H slowly rotates. It will also be observed that as the weight H' is lowered the longer sections 3 and 4 of the endless chain E^3 and lying between the roller G and the sprocket wheels E^2 and F^2 become shorter, again, however, without moving the sprocket wheel F^2 , the roller G slowly rotating as in the case of the roller H . When the weight H' has reached the limit of downward travel for which it has been adapted, the lower surface of the weight H' contacts with the upper end of the adjustable screw P^3 and depresses one arm of the lever P , thereby raising the opposite arm of said lever, and the rod L^5 , releasing, through the lever L , the cam pin L^3 from the stop recess K^{11} , also thereby releasing the governor stop arm K^{19} and permitting the actuation of the power-storage device D , thereby actuating the sprocket wheel Q , and through it and the sprocket chain Q' rotating the sprocket wheel F' and thereby the sprocket wheel F^2 in the direction of the arrows and by means of the endless chain E^3 raising the weight H' to its uppermost position, which movement is effected so smoothly, gradually and uniformly as to in no manner interfere with the accurate running of the clock, and since, during that operation, the weight H' still exerts its normal weight upon the sprocket wheel E^2 , there is not required any supplemental clock-train driving means such as is ordinarily used in other similar mechanism.
- 50 The apparatus shown herein is designed to release the lever P , and thereby, through the connected mechanism, raise the weight H' once every hour and at the same time the connected mechanism is arranged to strike the hour, but it will be evident that the apparatus may be so arranged as to wind at either less or more frequent intervals, and also that the striking mechanism may be arranged to strike more or less frequently, or may be dispensed with altogether as may be desired.
- 55 It is to be understood that this invention is not confined to the precise details of construction and arrangement of the invention herein set forth, as modification and variation may be made without departing from the spirit of the invention, as defined by the appended claims.
- 60 I claim:
1. The combination with a clock train of gravity-controlled operating means therefor, a time striking device, a power device, and means actuated by, and on a pre-determined limit of downward travel of, said gravity-controlled operating means, adapted to cause said power device to recurringlly raise said gravity-controlled operating means after 125

equal pre-determined periods of time and simultaneously actuate said time-striking device.

2. The combination with a clock train of flexible means for operating the same, including a weight, a time-striking device, a spring motor, a tripping member operatively connected to said spring motor, gearing and a second flexible means operatively connecting said spring motor and said first-named flexible means and weight, whereby, on the downward travel of said weight,

said tripping member is recurringly operated by the movement of the latter to actuate said spring motor and recurringly raise said weight through the flexible means specified after equal pre-determined periods of time and simultaneously actuate said time-striking device.

FRIEDRICH BANGERTER.
